(57) **CLAIM**

The ornamental design for a multi-rotor aerial vehicle, as shown.

DESCRIPTION

FIG. 1 is a front view of a multi-rotor aerial vehicle showing my new design.

FIG. 2 is a rear view thereof.

FIG. 3 is a left-side view thereof.

FIG. 4 is a right-side view thereof.

FIG. 5 is a top view thereof.

FIG. 6 is a bottom view thereof.

FIG. 7 is a front, right, top-side perspective view thereof.

FIG. 8 is a front, right, top-side exploded perspective view thereof.

FIG. 9 is a rear, left, top-side perspective view thereof.

FIG. 10 is a front, left, bottom-side perspective view thereof.

FIG. 11 is a rear, right, bottom-side perspective view thereof; and,

FIG. 12 is a rear, right, bottom-side exploded perspective view thereof.

The broken lines are included for the purpose of illustrating portions of the multi-rotor aerial vehicle that form no part of the claimed design.
